United States Patent Office

Des. 208,678
Patented Sept. 19, 1967

208,678

SUPersonic AIRPLANE

George S. Schairer, William H. Cook, and John D. Alexander, Bellevue, and Philip C. Whitener and Robert R. Wadleigh, Seattle, Wash., assignors to The Boeing Company, Seattle, Wash., a corporation of Delaware

Filed June 16, 1966, Ser. No. 2,694

Term of patent 14 years

(Cl. D71--1)

Fig. 1.

Fig. 2.

Fig. 3.

FIGURE 1 is a side elevational view of a supersonic airplane showing our new design;

FIGURE 2 is a top plan view thereof;

FIGURE 3 is a front elevational view; and

FIGURE 4 is a bottom perspective view.

The invention described herein may be manufactured and used by or for the Government of the United States of America for governmental purposes without the payment of any royalties thereon or therefor.

We claim:

The ornamental design for a supersonic airplane, as shown and described.
